UNITED STATES PATENT OFFICE.

CHARLES H. BOECK, OF JACKSON, MICHIGAN, ASSIGNOR TO NOVELTY MANUFACTURING COMPANY, OF JACKSON, MICHIGAN, A CORPORATION OF MICHIGAN.

HYDROCARBON-BURNER.

1,151,560.

Specification of Letters Patent. Patented Aug. 31, 1915.

Application filed January 11, 1915. Serial No. 1,497.

To all whom it may concern:

Be it known that I, CHARLES H. BOECK, a citizen of the United States, residing at Jackson, county of Jackson, State of Michigan, have invented a certain new and useful Improvement in Hydrocarbon-Burners, and declare the following to be a full, clear, and exact description of the same, such as will enable others skilled in the art to which it 10 pertains to make and use the same, reference being had to the accompanying drawings, which form a part of this specification.

This invention relates to hydrocarbon burners, and more particularly to heavy hydrocarbon burners.

In order to burn heavy hydrocarbon it must be vaporized either through the medium of a wick or by some means of heating the liquid.

20 The present burner relates to a form of heavy hydrocarbon burners in which the heavy hydrocarbon is thoroughly preheated and vaporized before it is mixed with the air necessary for combustion. Burners of this type are broadly old and it has been customary to control the flow of vaporized oil by means of a needle or similar valve. It has also been customary to utilize the port controlled by the valve for the purpose of 25 directing the vaporized fluid into the mixing chamber. This port must therefore be very small. Burners of this type have worked very satisfactorily for a short time. Then it has been found that carbon deposits 30 have accrued on the needle valve, in fact, the needle valve has practically become impregnated with the carbon so that the carbon cannot be removed, and the consequence has been that the flow of vaporized fuel through 35 the small port has been very much restricted and eventually will be practically stopped.

It is the object of the present invention to do away with this trouble in the port which directs the fuel into the mixing chamber.

45 Another object of the present invention is to provide uniformity of flame and heat over the entire upper surface of the burner.

Still another object of the structure hereinafter described is to provide a burner that is removable with respect to the generator and the stove proper.

A further object of this invention is an

arrangement and construction of the generator and burner so that heavy hydrocarbon is completely vaporized before being sprayed into the mixing chamber.

Figure 1 is a plan view of the burner and generator with a part of the slotted cap of the burner body broken away. Fig. 2 is a side view with some of the parts broken away and in section. Fig. 3 is a front elevation. Fig. 4 is a section of a portion of the fuel delivering pipe and the nozzle. Fig. 5 is a plan view of the burner mounted upon a part of the stove frame. Fig. 6 is a plan view of similar parts showing the burner in process of removal from the generator and the stove frame. Figs. 7, and 8 are a front and side view respectively of the plate which guides the burner as it is slid into or out of place. Fig. 9 is a section on the line A A of Fig. 5 showing the clip which aids in supporting the valve and generator.

The burner proper is formed by a shell *a* that incloses the main portion of the mixing chamber. The cap *b* fits over the cup-shaped shell *a* and completes the mixing chamber. This cap *b* is slotted as shown in Figs. 1 and 3.

The oil is carried through a pipe *c*, which forms a loop at the front of the burner and which leads into the pipe *d* that incloses the valve *e*. The loop when heat is applied to it is a gas generator, so it will be referred to as the generator. The pipes *c* and *d* will be referred to as a fuel conduit. It will be noted that the loop of the pipe *c* is directly at the front of the burner, and referring to Fig. 3 it will be seen that horizontal slots *m* are provided in the front of the burner shell *a* through which a flame may issue to preheat the oil in the coil of the pipe *c*. This preheating results in the vaporization of the oil so that when it enters into the pipe *d* that incloses the valve *e*, it is wholly vaporized. The vaporized oil issues from the pipe *d* through the nozzle *f* which screws into the end of the pipe *d*. It will be noted that the nozzle *f* is provided with a small perforation in its end and this is used to direct and restrict the vaporized oil. The vaporized oil is sprayed through a space *i* into the intake pipe *j* of the mixing chamber *h*. The space *i* is an air space and serves to allow the air

necessary to support combustion to enter the intake pipe *j* of the mixing chamber together with the vaporized gas.

One of the features of my invention is the making of the nozzle *f* removable with respect to the pipe *d*. Heretofore it has been customary to have the needle valve *e* govern the small port *g* but I propose to make a port *k* in the end of the pipe *d* which is governed by the needle valve *e*. It will be noted that the port *k* is quite large and that it leads into the removable nozzle *f* which has quite a small port *g*, only about 2/100 of an inch in diameter. Heretofore it has been customary to thrust the needle valve *e* into this small port *g* which directs the vaporized fluid into the intake pipe *j* of the mixing chamber, but as already explained in the introduction, the needle valve is liable to become coated with carbon which cannot be easily removed and this clogs the small port *g*. I obviate this difficulty by providing the small port *g* to direct and restrict the flow of the vaporized fluid into the intake pipe *j*, and by providing an additional larger port to be governed by the valve. The valve does not engage in the small port so that carbon collected upon the valve point does not tend to hinder the passage of the vaporized fluid.

On the contrary, the needle valve *e* engages in the comparatively large port *k* so that any carbon collecting upon this needle point does not materially interfere with the operation of the valve, for if any carbon does so collect, the valve need not be caused to approach quite so near the port as theretofore and the vaporized fuel will still flow through the port and no hindrance will result. If any carbon collects in the nozzle *f*, this may be easily removed by reason of the nozzle itself being removable.

Another feature of my invention is the use of the plate *l* which is seated in a recess provided for this purpose in the top of the shell *a*. This plate *l* serves to cover up the rear half of the mixing chamber and consequently causes the vaporized fuel and the air to flow to the front of the burner before it may rise. This not only gives a better mixture by prolonging the time of commingling of the air and the vaporized fuel but it also causes a more equal distribution of the flame and the heat arising from the flame. Heretofore it has been found that the rear portion of the burner affords a larger flame and a greater amount of heat than the front portion, but with this plate interposed between the slots of the cap and the mixing chamber, the combined vaporized fuel and air is required to flow to the front of the burner and then back over the baffle plate before it may issue from the top of the burner in the form of a flame. This also insures a proper distribution of the vaporized fuel and the air at the front of the

burner so that the flame may issue through the slots *m* to preheat the coil of the pipe *c*.

In Figs. 5, 6, 7, 8 and 9 there is shown my new form of removable burner. The generator is supported by means of the pipe *c*, which is united with a branch *n* of the main feed pipe *o* by means of the union nut *p*, and by the clip *q* which supports the pipe *d*. This form of construction securely holds the fuel pipe, generator and the valve in a definite position with respect to the stove frame. Heretofore it has been quite difficult to get at the burner and the generator because of the way these two elements were secured to the stove frame. It is to obviate this difficulty and to make possible the quick removal of the burner from both the generator and the stove frame that the present form of construction is designed. Upon the cross member *r* of the stove frame I secure a plate *s* either by welding, riveting or by any other suitable means. This plate *s* has its edges *t* turned over to form guides. A flat plate *u* is secured to the rear of the burner and is adapted to slide upon the plate *s* and in the guides *t*. The front of the burner has a strap *v* secured to it by riveting or other means and this strap projects upward and forward. It is provided with a perforation *w* adapted to register with the perforation in the clip *x*, which is secured to the pipe *d*. The plate *s* with its guides *t* (which will be termed the burner holder and guide) serve to guide the strap *v* so that the perforation *w* and the perforation in the clip *x* will register when the burner is made to approach the generator, as shown in Fig. 5. The winged screw *y* may then be inserted from underneath and the burner will thereby be firmly secured in position with respect to the generator and the other stove parts.

It will be understood that the burner can be removed without any trouble at all, either to get at the burner itself or to get at the generator. To remove the nozzle *f*, for instance, all that it is necessary to do is to unscrew the winged screw *y* by reaching underneath these parts, and then pull the burner to the rear as shown in Fig. 6 until the plate *u* comes out of the guides *t*, whereupon the burner may be lifted out, and the nozzle *f* unscrewed.

Cooperating with the horizontally disposed gas generator are a plurality of horizontally disposed slots *m*. These slots are substantially parallel with the legs of the loop of the generator and insure a much greater amount of heat being communicated from the burner to the loop than the old way of having vertical slots in the burner for in the latter a great deal of the heat intended for the generator is lost.

The burner is started by an alcohol, gasoline or other form of torch which is placed

under the coil of the pipe *c* to preheat the heavy hydrocarbon and vaporize it. After the burner itself has been started once, it continues this heating without the necessity 5 of the torch.

Although the burner is designed chiefly as a heavy hydrocarbon burner, I do not limit myself to a heavy hydrocarbon fuel as light hydrocarbons might be used and the 10 advantages of my invention enjoyed.

What I claim is:

1. In a hydrocarbon stove, the combination of a stove frame, a gas generator, a holder and guide, a burner adapted to be 15 slid into position with respect to the stove frame and the generator by being guided in said holder and guide, and a single device for detachably securing the burner in relation to the stove frame and gas generator.

2. In a hydrocarbon stove, the combination of a stove frame and a gas generator provided with a part having a perforation, a 25 guide and holder secured on the stove frame, a burner adapted to be guided with a horizontal movement by the holder and guide, a strap secured to the burner and having a perforation adapted to register with the perforation on a part of the stove frame and 30 generator, and a winged screw to fasten this strap to such part when said perforations are caused to register by the guiding of the burner in the holder and guide.

3. In a hydrocarbon stove, the combination of a frame, a gas generator supported thereon, a plate with turned over edges at the sides to form guides, said plate being secured to the frame, a burner provided with a plate on its bottom adapted to slide in said 40 guides of the first mentioned plate, and a strap secured to the burner and detachably securable to a part of the generator and stove frame when the burner is slid into position.

4. A hydrocarbon burner, having in combination, a fuel conduit including a vaporizer, said conduit having a valve-controlled orifice, a valve for controlling the same, a removable nozzle adapted to be detachably inserted in the end of the fuel conduit and 50 provided with a relatively small port, and

a burner bowl provided with a mixing chamber, the said burner bowl being detachably secured in position to the fuel pipe and movable away therefrom to allow access to the said removable nozzle.

55

5. A hydrocarbon burner, having in combination, a fuel pipe including a vaporizer, a pipe into which the fuel pipe leads, the said second mentioned pipe being provided with a large port, a valve in said second pipe 60 for governing the large port, a removable nozzle fitting into the end of said second pipe and provided with a relatively small port for directing the vaporized fuel, and a burner bowl having a mixing chamber, the 65 said burner bowl being detachably securable in a position with respect to said pipes and nozzle so that said nozzle delivers vaporized fuel through an intervening open space into the mixing chamber, and whereby access to 70 the removable nozzle may be had in case the same becomes clogged with carbon.

6. A hydrocarbon burner, having in combination, a fuel pipe including a vaporizer, a pipe into which the fuel pipe leads and 75 provided with a large port, a valve in said second mentioned pipe for governing the large port, a nozzle detachably securable to the end of the second mentioned pipe and provided with a relatively small port for directing the vaporized fuel, a burner bowl provided with a mixing chamber and an intake pipe, and detachable connections between the burner bowl, the fuel pipe and the second mentioned pipe for ordinarily sustaining the burner bowl in such position that the intake pipe thereof is in line with the said nozzle but spaced therefrom by an intervening open space through which the nozzle sprays the vaporized fuel, the said 80 burner bowl being removable with respect to the fuel pipe and the second mentioned pipe to allow access to the nozzle for removing carbon deposits.

In testimony whereof, I sign this specification in the presence of two witnesses.

CHARLES H. BOECK.
